CLAIM

The ornamental design for a sensor module, as shown and described.

DESCRIPTION

FIG. 1 is a top left front perspective view of a sensor module showing our new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom right rear perspective view thereof.

The even length dashed broken lines illustrate portions of the sensor module that form no part of the claimed design. Any views of the sensor module that are not shown in the figures form no part of the claimed design.
